DISHWASHER SPRAY ARM OR THE LIKE

Jack W. Claywell, Wisconsin Rapids, Wis., assignor to
Preway Inc., a corporation of Wisconsin

Filed Jan. 11, 1962, Ser. No. 68,274

Term of patent 14 years

(Cl. D49—1)

FIG. 1 is a front elevational view of a dishwasher spray arm embodying my new design;

FIG. 2 is a side elevational view thereof;

FIG. 3 is a rear elevational view thereof;

FIG. 4 is a section on an enlarged scale taken along the line 4—4 in FIG. 1;

FIG. 5 is a section on an enlarged scale taken along the line 5—5 in FIG. 1; and

FIG. 6 is a section on an enlarged scale taken along the line 6—6 in FIG. 1.

The broken lines shown on the drawing are intended to represent openings.

The side not shown is substantially like the side shown.

The dominant features of the design are shown in full line in the drawings.

I claim:

The ornamental design for a dishwasher spray arm or the like, as shown and described.
